UNITED STATES PATENT OFFICE.

CHARLES WILKINS, OF EAST FARNHAM, CANADA.

AUTOMATIC WATER-FEED FOR BOILERS.

SPECIFICATION forming part of Letters Patent No. 722,549, dated March 10, 1903.

Application filed July 31, 1901. Serial No. 70,310. (No model.)

To all whom it may concern:

Be it known that I, CHARLES WILKINS, a subject of the King of Great Britain, residing at East Farnham, in the Province of Quebec, Canada, have invented certain new and useful Improvements in Automatic Water-Feeds for Boilers, of which the following is a full and complete specification, such as will enable those skilled in the art to which it appertains to make and use the same.

This invention relates to apparatus for automatically supplying boilers with water; and its object is to provide an apparatus of this character which will not only automatically feed the water to the boilers as required, but will also automatically regulate the quantity of the water thus fed to the boiler and the time at which the water shall begin to feed and be cut off.

A further object is to provide an automatic water-feed for boilers which is simple in construction, effective and reliable in operation, and which can be readily applied to any boiler or hot-water apparatus.

To these ends the invention consists in an apparatus for automatically regulating the supply of water to boilers, &c., constructed substantially as hereinafter illustrated and described, and defined in the appended claims.

The drawing illustrates in elevation, parts being in section to show the construction, an apparatus for automatically regulating the supply of water to a boiler constructed in accordance with my invention.

The boiler A may be of any ordinary type and construction and is provided with a suitable support a for a regulating device, which consists, preferably, of a float-chamber a' and a valve-chamber a^2 , which are separated by means of the partition a^3 and are independent of each other, but both of which communicate, by means of suitable pipes, with the interior of the boiler A at a suitable point below the water-level thereof. The upper portion of the float-chamber a' communicates, by means of the pipe a^4 , with the steam-dome of the boiler A, whereby a constant pressure is maintained upon the water in said chamber, causing it to remain at the same level as in

the boiler. The float is connected, by means of a rod, to the beam a^5 , which is pivotally mounted in the partition a^3 , and to the other

end of the said beam is pivotally connected the rod or stem of the valve, inclosed within and operating against a suitable valve-seat 55 in the valve-chamber a^2 . The upper portion of the valve-chamber a^2 communicates, by means of a valved pipe, with the interior of the feed-tank B, which for convenience is shown mounted upon the boiler A. 60

The feed-tank B may be of any capacity suitable for its intended purpose and communicates at its upper portion by means of a suitable valved pipe b with the reservoir B' , which may be of any desired character and 65 located at any convenient point.

Within the tank B operates a float b' , which is connected by the rod b^2 to the slide-valve b^3 , which operates in a suitable valve-casing to open and close the ports communicating 70 with the piston-chamber b^4 . A suitable piston b^5 is mounted in said chamber and is adapted to reciprocate between the said ports, as will be readily understood. The rod of the piston b^5 is pivotally connected to an arm 75 of the bell-crank lever b^6 , which is pivotally mounted upon a suitable bracket-support secured upon the tank B and by which the piston-chamber b^4 is also supported. To the other arm of the bell-crank lever b^6 is pivotally linked the stem of the slide-valve b^7 , which operates in the valve-chamber b^8 to open and close the ports $d d'$, leading from the interior of the tank B to the atmosphere 80 and controlling the admission of the steam 85 from the boiler to the interior of the tank B through the pipe b^9 and port d' in an obvious manner. The steam is admitted to the valve-chamber b^8 from the boiler by means of the pipe b^9 and passes from the valve-chamber b^8 90 to the tank through the port d' when the valve is in the position shown in the drawings, at which time the port d , leading from the tank to the atmosphere, is of course closed. Steam is admitted to the valve-casing of the 95 valve b^3 by means of the pipe b^{10} , leading from the boiler A, as is clearly shown.

The position of the parts above described is that assumed when the boiler is supplied with sufficient water. When the water in the 100 boiler is lowered to such a level (which may be predetermined) as to cause the water to flow out of the float-chamber a' , thus causing the float therein to descend, the valve is

raised from its seat in the valve-chamber a^2 through the medium of the beam a^5 . The water will then flow from the tank B until the float-chamber is again filled, forcing the float upward to its normal position and closing the valve in the valve-chamber a^2 , thus cutting off the flow of water to the boiler. As the water is lowered in the tank B the float b' descends and the valve b^3 moves to admit the steam-pressure above the piston b^5 , forcing said piston downward and operating the valve b^7 through the bell-crank lever b^6 and connections to cut off the steam-pressure and open the ports communicating from the tank to the atmosphere, and thus permitting the water to flow into the tank B from the reservoir B'.

It is to be understood that the details of the construction shown and described herein may be altered at will without departing from the scope of the invention.

What I claim as my invention, and desire to secure by Letters Patent, is—

1. The combination with a boiler, of a feed-
25 tank having a steam-inlet port and an ex-
haust-port, a steam-pipe adapted to admit
boiler-pressure to said tank, a supply-reser-
voir communicating with said feed-tank, a
float arranged in said feed-tank and adapted
30 to be operated by the water therein, a slide-
valve adapted to open and close the commu-
nication between the steam-pipe and the tank
and between the tank and the atmosphere,
intermediary connections between said float
35 and said slide-valve, a regulating device
communicating with said boiler for controlling
the water-feed thereto, said regulating device
consisting of a valve-chamber communicating
with the said feed-tank and with the boiler, a
40 float-chamber communicating with the steam-
dome and with the boiler, a partition separat-
ing the two said chambers, a beam pivoted in
said partition, a float in said float-chamber

having its rod pivotally connected to one end of said beam and a valve in the said valve-chamber, having its stem pivotally connected to the other end of said beam, substantially as described.

2. The combination with a boiler, of a feed-
50 tank, a supply-reservoir communicating with
said feed-tank, a float arranged in said feed-
tank and adapted to be operated by the wa-
ter therein, a steam-cylinder mounted on said
tank, a valve-casing communicating with said
55 cylinder by suitable ports, a slide-valve in
said casing connected with said float and
adapted to open and close said ports, a piston
arranged in said cylinder and adapted to re-
ciprocate between said ports, a steam-pipe
connecting said valve-casing with the said
60 boiler, a bell-crank lever pivotally mounted
upon the cylinder-support and pivotally con-
nected at one end to the rod of said piston, a
steam-chest mounted on said feed-tank and
having inlet and outlet ports communicating
65 with said tank and with the atmosphere, a
steam-pipe connecting said steam-chest with
the boiler, a slide-valve connected to the other
end of said bell-crank lever and adapted to
control the said ports, whereby the steam may
70 be admitted to and cut off from the feed-tank
and the communication between the said tank
and the atmosphere opened or closed by the
movement of the said float, a regulating device
75 communicating with said boiler for control-
ling the water-feed thereto and a valved pipe
connecting the said feed-tank with the said
regulating device, substantially as described.

In testimony that I claim the foregoing as
my invention I have signed my name, in pres-
ence of the subscribing witnesses, this 25th
day of July, 1901.

CHARLES WILKINS.
